[21] Appl. No.: 28,529

[22] Filed: Apr. 9, 1979

[51] Int. Cl.² E01H 1/05

[52] U.S. Cl. 15/82

[57] **ABSTRACT**

An improved belt loader of the type used to remove

debris from a roadway includes an angled sweeping assembly comprising a pair of overlapping power driven rotary brushes with the downstream end of the lead brush overlapping the upstream end of the trailing brush so that the debris swept by both brushes is moved across the assembly and deposited by the side of the roadway.
